FOREIGN PATENT DOCUMENTS

WO 2016048161 A1 3/2013

Primary Examiner — David G Muller*(74) Attorney, Agent, or Firm* — Polsinelli PC; Adam C. Rehm(57) **CLAIM**

The ornamental design for a foot clip, as shown and described.

DESCRIPTION

FIG. 1 is a front, top, right side perspective view of a foot clip according to an embodiment of the new design;
 FIG. 2 is a front side elevation view thereof;
 FIG. 3 is a right side elevation view thereof, the left side elevation view being a mirror image thereof;
 FIG. 4 is a rear side elevation view thereof;
 FIG. 5 is a top plan view thereof;
 FIG. 6 is a bottom plan view thereof;
 FIG. 7 is a front, top, left side perspective view of a foot clip according to an embodiment of the new design;
 FIG. 8 is a front side elevation view thereof;
 FIG. 9 is a left side elevation view thereof, the right side elevation view being a mirror image thereof;
 FIG. 10 is a rear side elevation view thereof;
 FIG. 11 is a top plan view thereof; and,
 FIG. 12 is a bottom plan view thereof.
 Various embodiments of the foot clip are foreseen, which are disclosed and described using solid lines and broken lines, the broken lines forming no part of the claimed design.

1 Claim, 12 Drawing Sheets(56)
